United States Patent Office.

A. J. WARREN AND D. W. WILSON, OF WEST EAU CLAIRE, WISCONSIN.

Letters Patent No. 91,800, dated June 22, 1869.

IMPROVEMENT IN STEAM-GENERATORS FOR COMBUSTION.

The Schedule referred to in these Letters Patent and making part of the same.

To all whom it may concern:

Be it known that we, A. J. WARREN and D. W. WILSON, of West Eau Claire, in the county of Eau Claire, and State of Wisconsin, have invented a new and valuable Improvement in the Process for Consuming Sawdust as Fuel in Furnaces; and we do hereby declare that the following is a full, clear, and exact description of the construction and operation of the same, reference being had to the annexed drawings, making a part of this specification, and to the letters and figures of reference marked thereon.

Figure 1 of the drawings is a top sectional view of our device.

Figure 2 is a side view of the same.

Figures 3 and 4 are front view and sectional end view thereof.

Our invention relates to furnaces in which sawdust is used as fuel for making steam; and

It consists mainly in constructing and arranging, in a novel manner, pipes in which gas may be generated and conducted to the fire.

It also consists in adjusting automatic valves, in the spouts through which the sawdust is passed to the fire, which are opened by the weight of such sawdust, and close when no such substance is passing said spouts.

The letter A of the drawings represents a tubular boiler, enclosed in a shell or frame, and letters B are the fire-places thereunder, all constructed in the ordinary manner, except the grates of the fire-places are formed of small bars or wires, approaching very nearly together, and forming a species of web, upon which the sawdust may be held without seriously disturbing the draught of air.

The chief feature of our invention consists in the construction and arrangement of the gas-tube, marked C on the drawings.

It commences at the dome d, which forms a chamber over the top of the boiler, and passes from thence downward, as shown on fig. 2, and into one of the

side tubes of the boiler. It passes through said tube to the rear of the boiler, as shown on fig. 1; from thence across the rear of the boiler, returning to the front through a tube on the side opposite to that through which it entered, as shown on fig. 3. After thus reaching the front of the boiler, it is bent downward as low as the top of the fire-place, in the manner represented on fig. 3, crossing the front thereof, as shown.

At the points s we attach short pipes, that are turned inward to the fire-place.

We also attach a cock, v, at the point indicated, by which the flow of gas in the pipes may be regulated.

The function of this arrangement is to receive the gas that collects in the dome d, and conduct it through the boiler-tubes to the fire, receiving heat from the boiler upon the route, and generating additional gas therefrom.

The conducting-spouts for sawdust are marked E on the drawings.

The letters y are valves adjusted below the spouts, arranged to close when the sawdust has ceased running.

We disclaim all right of invention to anything shown in the patent of E. S. Chase, under date of May 18, 1869.

What we claim as our invention, and desire to secure by Letters Patent, is—

The apparatus for consuming sawdust herein described, having gas-tube C, boiler A, dome d, fire-places B, spouts E, and valves Y, constructed and arranged substantially as specified.

In testimony that we claim the above, we have hereunto subscribed our names, in the presence of two witnesses.

A. J. WARREN.
D. W. WILSON.
